CLAIM

I claim the ornamental design for a weight bench, as shown and described.

DESCRIPTION

FIG. 1 is a front perspective view of a weight bench, showing my design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a top plan view thereof;

FIG. 7 is a bottom plan view thereof;

FIG. 8 is a perspective view from another angle of view thereof;

FIG. 9 is a perspective view of the weight bench in an alternative state; and,

FIG. 10 is a perspective view of the weight bench in a second alternative state.

1 Claim, 10 Drawing Sheets
